UNITED STATES PATENT OFFICE.

WALTER EVERETT MOLINS, OF LONDON, ENGLAND.

WRAPPING OF CIGARETTES AND OTHER ARTICLES.

Application filed July 7, 1925, Serial No. 42,084, and in Great Britain July 10, 1924. Renewed August 1, 1928.

This invention relates to a method and apparatus for wrapping cigarettes and other articles and has more particularly for its object the provision of means whereby cigarettes may be packed in two or more wrappers at a greater speed than is possible with machines at present in use.

It has previously been proposed to provide a cigarette packing machine wherein each batch of cigarettes is carried by a reciprocating plunger which pushes one batch at a time into contact with two wrappers in succession, and into engagement with folding and sealing means arranged in the path of the plunger for the purpose of enclosing each batch of cigarettes in two wrappers, whereupon the plunger returns to its initial position to pick up another batch of cigarettes which is subjected to the same series of operations.

It will be appreciated that in a machine of the above character, wherein each batch of cigarettes is fed to the wrappers and folders by a reciprocating plunger, the throw of such a plunger is, in practice, limited and in consequence the number of wrappers which can be wrapped about a batch of cigarettes is also limited. Again, in practice it is found that the speed of a reciprocating plunger is limited beyond which the operation of a packing machine is very unreliable.

Further, in a machine operated by a reciprocating plunger, a period of time is wasted between the initial movement of one batch of cigarettes and the initial movement of the next succeeding batch, in which several batches of cigarettes might be packed. It is the object of the present invention to provide means whereby batches of articles (for example, cigarettes) are moved in close proximity one after the other into engagement with a series of wrappers, thereby ensuring that the number of batches of cigarettes which can be wrapped whilst the batches are travelling at a definite speed, is greater than is possible with a reciprocating plunger travelling at a corresponding speed.

The present invention consists of a method of packing cigarettes and other articles in two or more wrappers, wherein batches of ar-

ticles are moved simultaneously in a constant direction and rapid succession into engagement with wrapping strips fed across the path of each batch of articles in separate planes transversely disposed to said path. The expression "constant direction" used in connection with the movement of the articles is intended to imply movement in a straight or curved path as opposed to movement in a staggered or zig-zag path.

Further, the present invention consists of an apparatus for packing cigarettes and other articles in a series of wrappers which comprises a forwardly moving conveyor adapted to simultaneously move batches of articles in rapid succession into engagement with two or more wrapping strips fed across the path of each batch of articles in separate planes transversely disposed to said path.

Preferably the wrapping strips are fed continuously from a reel and are severed automatically as the articles come into contact therewith without interfering with the feed of the strips, the articles taking charge of the severed strips and carrying them through the various folding or other devices, but other forms of wrapper feeding devices may be used if desired.

One or more of the wrapping strips may consist of two or more strips preferably of different materials, superposed and manipulated as a single wrapper.

In a suitable arrangement for carrying out the invention and particularly applicable for wrapping bundles of cigarettes, the bundles are carried on an endless conveyor having pusher pieces as described in British patent specification No. 13,957 of 1915, the mouthpiece and ready-made cup or packet described in said specification being omitted. A series of wrapping strips are fed substantially vertically across the path of the moving bundles by means of apparatus substantially as described in British patent specification No. 165,891.

As each bundle meets the first wrapping strip, the latter is severed and wrapped round the bundle as described in the last-named specification and the wrapped bundle is car-

ried to the second strip and the severing and wrapping operation is repeated and so on for each of the series of strips.

Any or all of these wrappers may be 5 gummed and secured if desired at or between each stage of the wrapping by any known means, and gumming apparatus such as described in British patent specification No. 16,738 of 1924 may be employed.

10 For example, the first wrapper may be merely folded and the second wrapper gummed and secured to form a sealed outer container and a third and final wrapper may be of transparent tissue paper, wax paper or 15 other transparent paper to act as a protective coating.

With regard to the closing of the open ends 20 of the packages where they are in contact with the conveyor pusher pieces, this may be accomplished by using the tucking mechanism described in British patent specification No. 214,792, or its equivalent, the pusher piece 25 catching up the closed bundle after it has been tucked, this operation being repeated for the various wrappings.

The wrappers may be of any desired length, for example, the second wrapper may be shorter than the first and arranged to form 30 an outer cup or container of the height of the bundle, such a style of packet being in common use in the United States of America and in certain continental countries.

In this case the cigarettes may be wrapped 35 in a first wrapper consisting of metal foil lined with tissue paper, the double strip being fed as a single strip. After receiving this first 40 wrapper the bundle then moves to a second shorter wrapper which forms the outer cup or container and which may be gummed or sealed by any of the usual known means, folded down and dried.

The overlapping ends of the first wrapper 45 may be closed as aforesaid on the lines described in specification No. 214,792 or the bundle may be removed from the conveyor and the open end tucked and sealed by any other desired method.

To enable the invention to be fully understood, it will now be described by reference 50 to the accompanying drawings which illustrate a machine constructed according to one form of the invention and arranged for packing cigarettes in an inner wrapper of foil or the like, wrapping the foiled bundle in a short 55 wrapper forming a cup and finally enclosing the whole in a transparent wrapper, the operations of the machine being automatic and continuous.

In the drawings:—

60 Figs. 1, 2 and 3 are plan views of portions of the machine and if joined together consecutively will give a plan view of the whole machine;

Figs. 4, 5 and 6 are sectional side elevations

respectively of Figs. 1, 2 and 3 and if joined 65 together consecutively will give a side elevation of the whole machine;

Fig. 7 is a cross-sectional elevation of the gumming apparatus which may be employed, 70 and

Fig. 8 is a plan view of one side of the apparatus shewn in Fig. 7.

Fig. 9 is a side elevation of a gum pot, the view being in the direction of the arrow Y 75 in Fig. 7;

Fig. 10 is a plan view, and Fig. 11 is a side elevation of the tucking mechanism which may be employed.

Figs. 12 to 15 inclusive are views in perspective shewing the various stages of the 80 wrapping of the cigarette bundles.

As shewn, the machine comprises a bed 1 with a central slot 2 through which pusher pieces 3 of a chain conveyor run. Each pusher is fitted with a spindle 4, the ends of which are connected to conveyor chains 5 carried on driving sprocket wheels 6 and idlers 7.

The driving sprocket wheels 6 are carried on a shaft 8 running in bearings in the machine bed and having a bevel gear 9 mounted at one end thereof, the drive being transmitted from a main shaft 10, mounted in bearings 11 on the side of the machine bed through a bevel wheel 9a. The shaft 10 is driven by a pulley, clutch or any other means from a suitable source of power and rotates in such a direction that the pusher pieces 3 travel in the direction of the arrow D, Figs. 4, 5 and 6.

Bunches 12 of cigarettes are fed to the machine bed by a hopper or any known means 100 and are carried along the bed by the pusher pieces 3. This method of moving cigarettes is fully described in British specification No. 13,957 of 1915 for example. The cigarettes controlled by side guides 13 are moved along the bed until they meet a substantially vertical sheet R of tin foil, foil and tissue, or other lining material, which is fed continuously downwards through a slot 14 in the bed.

The lining material R is preferably obtained from a reel 15 mounted above the bed and is pulled down by rollers 16 and 17, continuously rotating in the direction of the arrows S, Fig. 6. A strip of the desired length is cut from the web R just after the sheet has been gripped between the cigarettes and the folding box T in the known manner.

The feeding gear for the web R is carried on a bar 19, mounted on two screwed, adjustable pillars 20. A roller bracket 21 screwed to bar 19 carries a rotating spindle 22 to which is secured the roller 16. This roller is preferably rubber covered.

One end of the spindle 22 carries a bevel gear 23 meshing with a bevel wheel 24 on a vertical shaft 25.

The wheel 24 is driven by a bevel wheel 26

mounted on a shaft 27 mounted in a bearing bracket 28 and at the other end of shaft 27 a sprocket wheel 29 is mounted which is driven by another sprocket wheel 30, carried on the main shaft 10. The roller 17 is an idler and is mounted on a spindle 31 carried by a yoke 32, pivoted at 33 to a pivoted bracket 34 swinging on a pin 35 in the bar 19.

A spring pin 36 is mounted on the bracket 34 and a spring 37 is stretched from the pin 36 to another pin 38 in the bracket 28. This arrangement causes the roller 17 to make contact with roller 16 under the tension of the spring 37, the pivoted yoke permitting the rollers to lie parallel. The roller 17 may be of steel or rubber covered if desired.

A handle 38^a is fitted for separating the rollers when necessary, for example, when passing down the web of a new reel.

The knife 18 is screwed to a hinged block 39 which is thicker than the knife blade and is pivoted at 40 to a bar 41 which is clamped to the vertical spindle 25. The pivot 40 extends downwards and is fitted with a torsion spring 42. As the knife rotates a portion of the block 39 comes into contact with an adjustable stop pin 43 which causes the knife to bend backwards until the block can slip past the stop, when the knife straightens out under the action of the spring and cuts the web R. The web passes between the guides 44 and 45 against which it is cut by the knife. It will be understood that the pin 43 is of such a length that it makes contact with the block 39 only and does not arrest the actual knife blade.

Scrapers 46 and 47 are fitted to rollers 16 and 17 to assist in stripping the web in case there is any tendency for it to stick.

The moving cigarettes meet the strip and as it is cut, push it into the folding box T comprising a top plate 48 carried by a bridge 49, supported on pillars 50, side folders 51 and the machine bed. The folders 51 form the narrow side tucks in the liner at a, Fig. 12.

As the wrapped bundle moves onward, the upper side flaps b, Fig. 12, are bent down by the spiral folders 52, and lastly, the lower side flaps c are turned up by another pair of spiral folders 53 screwed to the machine bed. The result of these folding operations is the wrapped bunch shewn in Fig. 12, which is open at one end.

The wrapping mechanism above referred to is further described in United States of America specification No. 1,468,246.

The wrapped bunch moves further along the bed between guides 54 and its closed end then meets another vertical sheet.

In this case the sheet is adapted to form the printed outer cover or packet usually used for cigarettes. A pile of separate sheets or blanks is placed on a table 55 (Fig. 2), the blanks being positioned by a back stop 56, side guides 57, long guides 58 and front guides

75^a. At the end of guides 58 a small roller 59 is mounted over which the blanks run as they are removed from the magazine one at a time by suction tubes 60. The tubes 60 are connected to a suction tube 61, mounted on a quadrant 62, a pin 63 on the quadrant being adapted to oscillate in a long bearing 64.

The oscillating motion causes the ends of the suction tubes 60 to swing up and touch the lowest blank in the magazine and as they return to drag the blank out of the magazine and down on to rotating rollers 65.

As the suction tubes reach their lowest position a roller 66 is swung into contact with the top of the blank. This causes the blank 80 to feed forward and down between the large rollers 67 and 68. Of these rollers the upper roller 67 is an idler, spring pressed into contact with the lower roller 68, the latter being 85 suitably driven.

The blank passes out beneath a guide 69 and between roller 68 and a directing roller 70 which cause it to pass vertically downwards through a slot 71 in the machine bed.

The roller 70 which may be rubber covered, 90 is carried in an arm 72 attached to another arm or lever 73. The latter is pivoted at 74 to the top bridge 75 of the feed frames 76.

A lever 77 and spring 78^a press on the arm 73 and hold roller 70 securely in position. 95

When necessary lever 77 may be swung out of position by knob 78 and the arm 73 raised.

The method of operating the suction tubes 60 and the roller 66 is as follows:—

A cam 79 on the shaft 80 of roller 68 makes 100 contact with a cam roller 81 on a lever 82, the latter being pinned to a shaft 83 carried in bearings in the feed frames. The roller 66 is mounted in a fork 84 carried on the shaft 83, a plate 66^a on the fork being arranged to 105 keep the fronts of the blanks in the magazine in register by patting them as the fork is oscillated.

An arm 85 on the fork 84 is connected by a link 86 to a point on the quadrant 62. The motion of cam 79 causes the shaft 83 to oscillate, thus rocking the fork carrying the roller 66 and also causing the suction tubes 60 to oscillate about the pin 63.

A spring 87 is connected to a lever 88 at 115 one end and to a pin 89 on the frame at the other, the lever 88 being fixed on the shaft 83, thus returning the parts to their original position.

The drive for the above blank feeding mechanism is taken from a bevel wheel 90 on the main shaft 10 of the machine. The bevel wheel 90 meshes with a bevel wheel 91 on a vertical shaft 92 running in a bearing bracket 93 fixed to the side of the machine bed. At its upper end the shaft 92 is fitted with another bevel wheel 94 meshing with a bevel wheel 95 on the shaft 80. An extension of shaft 80 carries a sprocket wheel 96, connected by a chain 97 to a sprocket wheel 98 130

on shaft 99 on which the rollers 65 are mounted.

Beyond the blank feeding mechanism another folding box is located and a vertical blank guide 100 is also provided.

The folding box consists of a top plate 101, side folders 102 and the machine bed.

The wrapped cigarettes, Fig. 12, are carried along by the conveyor and meeting the vertical sheet, push it into the folding box. This operation forms the narrow end tucks d, Fig. 13.

The folders 102 in this case are long and extend as far as the gumming apparatus about to be described.

Just before reaching the gumming apparatus, the lower side flaps e (Fig. 13) of the paper packet are turned up by the folders 103. These folders are similar in shape and function to the folders 53, but they are extended past the gumming position and are provided with a slot 104 through which the gum wheels project.

The gumming apparatus is shewn in Figs. 5, 7, 8 and 9.

As shewn, horizontal gum wheels 105 are used, rotating in gum pots 106. Each wheel is mounted on a pin 107 and is rotated by a spindle 108 which is carried in a bearing 109 and is fitted with a bevel wheel 110 which gears with a bevel wheel 111 on a cross shaft 112. The cross shaft 112 is fitted with a pinion 113 at one end which gears with a pinion 114, running on a pin and fixed to a sprocket wheel 115, driven by a chain 97. The cross shaft 112 and the bevel wheels are all supported in a bridge 116 which has tongues 117 at its ends fitting in slots in side brackets 118 which are fixed to the machine bed.

The spindles 108 are connected to the gum wheels 105 by means of screws 119 which are fixed in the gum wheel bosses with their ends engaging grooves in the ends of the spindles. By this arrangement the whole of the upper driving gear can be lifted out of the way when necessary. Springs 120 furnished with finger hooks 121 keep the bridge 116 in position.

Each gum wheel has a small sector 122 of steel, hard brass or the like and the shape of the slot through which the wheel emerges is as shewn in Fig. 9. A scraper 123 is fitted which rubs against the rim of the wheel and is provided with a slot 124 through which a stream of gum can emerge. The sector 122 clears out this slot at every revolution and prevents the orifice being closed by dried gum or dirt. The sector itself is rubbed free of gum by the scraper and the wheel is timed so that the position of the sector coincides with the part of the packet marked, Fig. 13, and no gum is applied to this part. This gumming apparatus is also described in British specification No. 16,738 of 1924.

After gumming, the packet meets another

pair of folders 125 which fold down the upper side flap g, Fig. 13.

Shortly after this, the moving packet is gripped between a pair of tucking wheels 126 shewn in detail in Figs. 10 and 11. These wheels are described in United States of America specification No. 1,517,307 and are fitted with tucking pawls 127 which operate to fold down and tuck in the narrow end folds of the open end of the inner wrapper 75 of the packet, all as described in the aforesaid specification. The wheels 126 comprise two discs with parts of the rims cut away. The remaining portions of the rims may be rubber covered. The wheels are fitted with 80 tucking pawls 127 pivoted at 128 and pressed outwards by springs 129 and also with spin-dles 130 having bevel wheels 131 at their upper ends.

A cross shaft 132 carried in brackets 134 85 is fitted with bevel wheels 133 which gear with the wheels 131. This mechanism is driven by a sprocket wheel 135 at one end of the cross shaft 132 driven by a chain as shewn. After the narrow end folds have 90 been tucked, the bottom flap of the end of the wrapper is bent up by arms 145 pivoted to the bed at 146 and pushed up by the passing conveyor spindle 4, which makes contact with the under sides of the arms.

On the spindle 132 are mounted two cams 138 and 139. The cam 138 works against a roller 140 mounted on a tucker 141 which is pivoted at 142 to the plate 143. A spring 144, Fig. 10, causes the tucker to move down when the drop in the cam is reached. This tucker operates when a packet has reached the position shewn in Fig. 5 with the narrow end folds of the inner wrapper tucked and the bottom flap bent up, and depresses the top 105 flap of the inner wrapper.

During these operations, the packet is held stationary by a levelling flap 147 carried by one arm of a lever 148 pivoted at 149, the other arm of the lever carrying a cam roller 150 110 engaging the cam 139. The speeds of the conveyor and the cam 139 are so timed that the flap 147 rises and falls, releasing a packet before the conveyor brings another into position.

The packet is then moved by the conveyor between heated guides 151 which dry the gum which has been applied to the sides of the outer wrapping and the packet meets a further wrapping strip which is preferably of a transparent material and is designed to form a final wrapper, totally enclosing the packet.

This wrapper X is fed vertically across the path of the packet from a reel V, Fig. 4, and is cut by mechanism similar to that previously described with reference to Figs. 3 and 6 and the moving packet carries the cut strip through folders and gumming apparatus similar to that described with reference to 130

Figs. 2 and 5. In Figs. 1 and 4, the wrapping mechanism is indicated at 160, the gumming mechanism at 161 and further description of these mechanisms is thought to be 5 unnecessary.

After folding and gumming the packet is passed through heated guides 152 and discharged from the machine. The packet is thus left with a sealed inner wrapper, an 10 outer cup open at one end and a wrapper enclosing the whole with a block bottom, but open at the other end as shewn in Fig. 15. The end flaps of the open end of the final 15 wrapper may now be closed by apparatus of the kind shewn in Fig. 5 or in any other desired manner. The sealing may be by gum or by a stamp.

In some cases the final wrapper may be of waxed paper and the folds secured by melting the wax in the known manner. 20

It will be understood that although the machine described is adapted to enclose the cigarettes after their first wrapping in an open ended cup, that it may readily be adapted by substituting the appropriate mechanism to enclose the wrapped cigarettes in a closed outer packet or wrapping instead of a short cup.

In forming the cup, as above described, 30 cut sheets fed by suction means have been illustrated, but other methods of feed may be employed for the cut sheets.

Further, instead of cut sheets, a continuous web and cutting mechanism as described 35 with reference to Figs. 3 and 6 for example, may be employed, the length of wrapping strip cut off being adjusted to form the cup.

Instead of a continuously moving conveyor, 40 the articles may be moved by an intermittently forwardly moving conveyor.

Obviously the several mechanisms may be arranged in various combinations to wrap cigarettes in any desired number and style 45 of wrappings and the positions of the various units may be interchanged without departing from the invention.

The invention is also applicable for wrapping articles other than cigarettes.

Having thus described the nature of my 50 said invention and the best means I know of carrying the same into practical effect, I claim:—

1. A method of packing cigarettes and 55 other articles in two or more wrappers wherein batches of articles are simultaneously moved in a constant direction and rapid succession into engagement with wrapping strips fed across the path of each batch of articles 60 in separate planes transversely disposed to the said path.

2. An apparatus for packing cigarettes and 65 other articles in a series of wrappers which comprises a forwardly moving conveyor adapted to move batches of articles simulta-

neously in rapid succession into engagement with two or more wrapping strips, means to feed said strips across the path of each batch in separate planes transversely disposed to said path. 70

3. Apparatus for packing cigarettes and other articles in a series of wrappers which comprises a forwardly moving endless belt conveyor, adapted to support and simultaneously move batches of articles into engagement with wrapping strips, means to feed said strips across the path of each batch in separate planes, transversely disposed to the said path, and means for automatically folding, tucking and sealing one of the wrappers 80 around the articles. 75

4. An apparatus for packing cigarettes and other articles in a series of wrappers which comprises a forwardly moving conveyor adapted to move batches of article simultaneously in rapid succession into engagement with a plurality of continuous wrapping strips, means to feed said strips across the path of said batches in separate planes transverse to said path, mean to cut said strips 90 when a batch of articles engages the same, and a series of folders to receive the cut 95 wrappers and articles. 85

5. An apparatus for packing cigarettes and other articles in a series of wrappers which comprises a forwardly moving conveyor adapted to move batches of articles simultaneously in rapid succession into engagement with a plurality of continuous wrapping strips, means to feed said strips across the 100 path of said batches in separate planes transverse to said path, mean to cut said strips when a batch of articles engages the same, means to fold each cut wrapper over the top, bottom and front end of a batch, means to 105 tuck, fold and gum the sides of at least one wrapper, and means to fold and close one of the open rear ends of said wrappers. 95

6. An apparatus for packing cigarettes and other articles in a series of wrappers which 110 comprises a forwardly moving conveyor adapted to move batches of articles simultaneously in rapid succession into engagement with a plurality of continuous wrapping strips, means to feed said strips across the 115 path of said batches in separate planes transverse to said path, mean to cut said strips when a batch of articles engages the same, and a series of folders to receive the cut 120 wrappers and articles, the first applied wrapper covering the batch of articles completely, the second wrapper being open at one end and serving as a cup, and the last wrapper being adapted to completely enclose the first two mentioned wrappers. 125

7. An apparatus for packing articles in a series of wrappers, comprising in combination, a continuously moving conveyor adapted to move batches of the articles simultaneously into engagement with a plurality of 130

wrapping strips, means to feed said strips from continuous supplies thereof across the path of said batches in separate planes transverse to said path, means to cut each said strip when a batch of articles engages it, an additional wrapping strip adapted to be fed into the path of each batch from a cut magazine thereof, suction means to remove each said additional wrapping strip from said magazine and folding means for the various strips to cause them to enclose the articles.

In testimony whereof I have signed my name to this specification.

WALTER EVERETT MOLINS.
